BY *Oberlie, Limbach & Day*
ATTORNEYS.

UNITED STATES PATENT OFFICE

2,282,915

HEAT CONTROL SYSTEM FOR PRESSURE
CASTING MACHINESDaniel D. Whyte, New York, N. Y., assignor to
Lester Engineering Company, Cleveland, Ohio,
a corporation of Ohio

Application September 19, 1939, Serial No. 295,613

2 Claims. (Cl. 219—20)

This invention relates, as indicated, to a heat control system for pressure casting machines and more particularly to a method whereby the temperature to which the material to be cast is heated may be automatically regulated.

In machines for the pressure casting of materials generally known as "plastics," such as the machine disclosed in the application for U. S. Patent of Nathan Lester, Ser. No. 174,175 filed November 12, 1937, some difficulty is often experienced in maintaining the temperature to which the finely divided or powdered material is heated at a designated level. It will be understood that in the operation of machines of the type referred to the dry "plastic" is introduced to the pressure casting cylinder, there rendered plastic by heat from an electric heating jacket, and then forced through an injection nozzle into the die. There is, of course, an ideal temperature to which each material should be heated to secure precisely the proper degree of plasticity. However, since the machine is operated with considerable rapidity, a practical difficulty arises in that there occurs a "lag" in the rate of application of heat with respect to its rate of withdrawal caused by the introduction and discharge of material to be cast. As a result, although the temperature of the casting cylinder might be at the ideal when material is first introduced, controlled heating systems heretofore known are not capable of anticipating this temperature drop, and when they do not operate to compensate for it, it is too late because the material has left the cylinder. Hence, a contrary condition occurs tending to produce a temperature rise above the ideal. Such fluctuation in the temperature of the material is of course strictly to be avoided since too low a temperature will not cause the proper degree of plasticity and too high a temperature may result in streaks or "burns" in the finished article. For most "plastics" there is a well known temperature at which the material should be maintained.

It is, therefore, a primary object of this invention to provide a heat control system for pressure casting machines and the like whereby the temperature to which the material to be cast is heated may be maintained substantially uniform and at any desired point.

A further object is to obtain the above result automatically, the means provided being adjustable depending on the material employed.

Other objects of this invention will appear as the description proceeds.

To the accomplishment of the foregoing and

related ends, said invention, then, consists of the means hereinafter fully described and particularly pointed out in the claims, the annexed drawing and the following description setting forth in detail certain means and one mode of carrying out the invention, such disclosed means and mode illustrating, however, but one of various ways in which the principle of the invention may be used.

In said annexed drawing, Fig. 1 is a fragmentary elevational view, partly in cross-section, of an improved pressure casting machine; and Fig. 2 is a diagrammatic layout of the electric circuits of the temperature control means.

Referring now more particularly to said drawing, the machine illustrated comprises a hydraulic cylinder 1 in which a piston and piston rod are adapted to reciprocate. A material feed hopper 2 feeds measured charges into the pressure casting cylinder 3 where such material is heated by the electric heating jacket 4 and ejected through the nozzle 5 by action of an annular plunger 6 in turn actuated by said hydraulic cylinder. Also shown are die plates 7 and 8 and knock-out paddle 9. For a complete description of the machine reference may be had to the specification of the above mentioned application Serial No. 174,175.

As ordinarily operated, the heating coil is regulated by means of a thermostat adjacent said cylinder 3. Whenever the temperature drops below an appointed minimum the circuit is automatically closed until the proper temperature is regained. Of course, the thermostat is unable to anticipate what the heat requirement will be for each step in the casting cycle and as a result considerable fluctuation arises.

A typical casting cycle may be as follows: A measured charge of the dry material is fed into the casting cylinder 3, the plunger 6 descends, plasticizing and injecting the material into the dies. Then the dies are opened and the casting ejected while said plunger returns to its starting position and another charge of dry material is fed. After a dwell interval which is usually somewhat variable the cycle is repeated.

It is apparent that considerable heat will be required in the first stages to raise the temperature of the dry material but that less heat will be needed as the plasticized material is forced into the dies. The thermostat naturally lags somewhat and as a result the casting cylinder 3 is too cool in the first stage of the cycle and too hot thereafter. If the thermostat be such as to ensure a sufficiently high temperature in the

first stage, then the molded article may be streaked and "marbled." If the temperature is too low, then nozzle 5 will be plugged by the insufficiently plastic material and operations must be temporarily suspended until it is cleared.

I have avoided the above difficulties by the provision of two heating circuits, the one thermostat controlled but set for a temperature too low to cause any damage, and the other regulated to supply the necessary additional heat at 10 and for just the proper time.

These circuits and their controls are shown diagrammatically in Fig. 2. The line L₁ leads to thermostat 10, which when closed also causes the closing of relay switch 11, and thence out to line L₂. With said relay switch closed current passes through heating coil 12 until a temperature is attained at which said thermostat again opens and said relay switch follows suit. By the closing of plunger limit switch 13 current may be passed through said heating coil even when said thermostat is open, thus anticipating a sudden increase in heating requirements. This result is obtained as follows: switch 13 is closed energizing clock motor M and clutch C whereby contacts 14 and 15 are closed. Current now passes through the following circuit, L₁, heating coil 12, contacts 15, and L₂. When limit switch 13 is opened contacts 14 and 15 remain closed, maintaining said motor and clutch circuits and the auxiliary heating circuit. At the end of the preset interval said clock motor trips said contacts 14 and 15 breaking said motor and clutch circuits and said auxiliary heating circuit. The cycle is then ready to repeat.

Said motor, clutch, contacts, etc. form the conventional "timer" which may be purchased as a unit and installed on the machine as is the timer 16 shown in Fig. 1.

In operation, dry material is fed into the cylinder 3 and plunger 6 descends, arm 17 moving therewith and closing plunger limit switch 13. The current passing through coil 4 heats the material to the proper temperature for plasticizing and the same is forced through nozzle 5 into the dies. When plunger 6 with arm 17 rises, the switch 13 is opened but as above pointed out this does not affect the circuits carrying current to coil 4 or timer 13. These are broken by said clock motor after the passage of the interval for which it was set, whether before or after the return of the plunger. If the temperature now drops below the minimum of the thermostat 10, the other heating circuit will again be closed as above described until such temperature is regained.

It will readily be seen from the foregoing description that the timer 16 may be set to anticipate the suddenly increased heat requirement when a charge of dry material is about to be plasticized and also to cut out when such heat is no longer required. The time may be adjusted

5 to satisfy the requirements of any particular material or quantity thereof. As a result, expensive delays and wastage are eliminated so that the production capacity and efficiency of the machine are maintained.

Certain modifications are apparent whereby the principle of this invention may be employed in connection with various types of casting machines. For example, separate heating coils may be employed for the thermostat and the timer controlled circuits. Or, especially when the machine is operated with great rapidity, the thermostat controlled circuit may occasionally be dispensed with. Furthermore, the switch 13 may be operated by other mechanism moving in connection with said plunger instead of by an arm attached directly thereto. All such modifications are clearly within the scope of the present invention.

20 Other modes of applying the principle of my invention may be employed instead of the one explained, change being made as regards the means and the steps herein disclosed, provided those stated by any of the following claims or 25 their equivalent be employed.

I therefore particularly point out and distinctly claim as my invention:

1. In a pressure casting machine wherein successive charges of material are heated to a predetermined temperature prior to being injected into a die, a casting cylinder into which such successive charges are measured, an electric heating element for heating said cylinder, a circuit including said element, a switch in said circuit, a thermostat adjacent said cylinder operative to close said switch when the temperature of said cylinder reaches a predetermined minimum, a second circuit including said heating element, time control means for said second circuit operative to close said second circuit for a predetermined period of time, and means associated with such casting machine for automatically setting said time control means in operation.

2. In a pressure casting machine wherein successive charges of material are heated to a predetermined temperature prior to being injected into a die; the combination of a casting cylinder having a plunger operable therein; and a heat control system for said cylinder comprising an electric heating coil about said cylinder, a circuit including said coil, a switch in said circuit, a thermostat adjacent said cylinder operative to close said switch when the temperature of said cylinder reaches a predetermined minimum, a second circuit including said coil, time control means for said second circuit operative to close said second circuit for a predetermined period of time, and means connected with such plunger for automatically setting said time control means in operation.
